CONTACT BANK FOR 25-POINT 10-WIPER ROTARY SWITCHES

Kenneth W. Graybill, Elmhurst, and Hans Sengebusch, Villa Park, Ill., assignors to Automatic Electric Laboratories, Inc., Chicago, Ill., a corporation of Delaware

Application February 16, 1950, Serial No. 144,521

17 Claims. (Cl. 175—306)

1

This invention relates to switch banks in general and more particularly to switch banks for one or two motion switches.

An object of this invention is to provide a contact bank for a one or two motion switch which comprises cheaply fabricated parts, easily assembled and yet accurate and efficient in operation.

In keeping with this object, a feature of the invention is the novel construction of the insulator elements which when assembled into a completed contact bank hold the metallic contacts stationary and prevent all lateral and longitudinal movement thereof.

Another feature of this invention is the provision for slightly bowed contacts further restricting the possibility of longitudinal contact slippage.

A further feature of the invention resides in the degree of compressibility afforded by the insulators.

Still another feature of the invention lies in provision for maintaining close tolerances in both overall dimension and the distances between the various levels of contacts.

These and other features will be pointed out in the ensuing specification and appended claims, reference being had to the accompanying drawings in which:

Fig. 1 is a plan view of an insulator element of the contact bank.

Fig. 2 is a cross section of the insulator element along line AA in Fig. 1.

Fig. 3 is a cross section of the insulator element along line BB in Fig. 1.

Fig. 4 is a cross section of the insulator element along line CC in Fig. 1.

Fig. 5 is a partial plan view of two contact strips as they would be arranged with relation to the insulator element adjacent a perforation for the compressing means.

Fig. 6 is a partial front view showing a pileup of insulator elements, contact strips, clamping plates and compression means.

Fig. 7 is a cross sectional view of a pileup along line DD in Fig. 5 and evidences a stack of insulator elements, contact strips, clamping plates and compression means and particularly depicts the bowed contact strip.

Contact banks for one or two motion switches have generally been made by clamping together a pileup of insulators with a plurality of metal contact strips spaced apart therebetween. The insulators were generally flat, solid and substantially incompressible, necessitating very close

2

production tolerances in order to have the distance between rows of contacts and overall dimensions of the bank meet operating requirements. But an even greater trouble factor exists in conventional contact banks, namely slippage of the contacts from their original placed positions, and such slippage is either lateral, longitudinal or both.

The inventors have in this invention provided 10 a molded, shaped insulator element. Because of relatively small area raised edges on the insulators, there is a sufficient degree of compressibility to facilitate maintaining close tolerances for both overall dimensions of the contact bank 15 assembly as well as distances between the various levels of contacts therein.

The invention further provides in the form of the insulators means to slightly bow the contact strips upon compression of the bank assembly as 20 well as seats and shoulders for the contact strips to engage so as to eliminate all possibility of slippage, either laterally or longitudinally. A notch in the contact itself to engage an insulator shoulder lends itself even further to this end.

Having generally described our invention, now, 25 with reference to figures and numbered components we shall describe the invention in greater detail.

Referring again to the structure illustrated in 30 Figs. 1-7 inclusive, the contact bank consists of metallic contact strips 1, molded insulator elements 2, clamping plate 3 and compression means 4.

The insulator elements 2 are molded so that 35 all edges, upper and lower will be raised. The upper raised edges right and left will themselves alternately have shoulders 5 and depressions 6. The lower raised edges right and left likewise alternately have elongations 7 and recesses 8. Shoulders 5 will all be immediately above lower 40 recesses 8 and lower elongations 7 will all be immediately below depressions 6. All shoulders 5, right and left are in line longitudinally and similarly all depressions right and left, lower elongations right and left and recesses right and left, 45 will be longitudinally aligned respectively. Upper depressions 6 are of a depth equal to the sum of the thickness of a contact strip 1 plus the depth of a lower elongation 7. The upper shoulders 5 are in height equal to the depth of adjacent depressions 6, and likewise, lower elongations 7 are equal in length to the length of adjoining recesses 8. Longitudinally between corresponding pairs of lower elongations 7, right and left, is 50 a semi-cylindrical appendage 9 which will be

55 a semi-cylindrical appendage 9 which will be

slightly greater in height than one elongation of its aligned pair of lower elongations, substantially equal to the other and equal in width to both. As shown in Fig. 7, the semi-cylindrical appendage 9 cooperates with the depressions 6 and elongations 7 to cause contact strip 1 to bow beneath the appendage 9. Right depression 6 is lower than left depression 6 for the purpose of producing nearly all of the displacement caused by the bowing of strip 1 at the terminal end of contact strip 1, while the contact end of the strip remains substantially horizontal. As shown further in Fig. 7, and also in Figs. 2, 3 and 4, right elongation 7 is longer than left elongation 7, for the purpose of fitting into the corresponding depressions 6 to give a firm interlocking relationship between adjacent supports and maintain the proper bow in the contact strips. Longitudinally between corresponding pairs of upper shoulders 5, right and left, are raised rings 10 integral with the insulator element 2, and which are reinforcements for perforations or bores 11 extending thru said raised rings 10 and the insulator elements. These bores or perforations are for accepting suitable compression means when a group of such like insulator elements are stacked in a pileup.

These insulator elements may be molded from any plastic or synthetic resin material such as a phenol condensate product and in a particular embodiment, polyethylene may be used. The overall shape of the insulator element will depend upon the type switch to which it is to be adapted. For standard Strowger type switch banks or rotary switch banks, the plan shape may be a semi-circular one as shown in Fig. 1, with pairs of corresponding components such as upper depressions fore and aft arranged radially thereon. However, the inventors do not wish to limit their invention to a semi-circular bank as it is equally adaptable to a rectangular type arrangement with the depressions fore and aft equally spaced apart, or for that matter, to any suitable geometric form.

Contact strips 1 are then laid longitudinally in aligned pairs of upper edge depressions 6. The contact strips may be cut or stamped from any suitable conducting material, preferably brass or Phosphor bronze. The strips as shown in Fig. 5 have an overall wedge shape for use in a radial spaced apart arrangement. Their shape could just as readily be rectangular for use in a parallel spaced apart arrangement. This seating in depressions 6, assumes a fixed position for the contacts without lateral movement. Along one lateral edge of each strip 1 is cut an obtuse isosceles angle 12 whose vertex will be at the center point both laterally and longitudinally of the strip. This large angular cut is positioned so that the contact may circumvent the compression means passing thru bore 11 to be described hereinafter, eliminating the possibility of a short circuit. The stamped strips may all be cut from one die for by merely overturning every other one, the arrangement shown in Fig. 5 may be accomplished, namely having lateral sides of contact strips having angles 12 cut therefrom facing one another while lateral sides not so notched will likewise be adjacent.

Another notch 13, is cut into an edge of contact strip 1, and may be of any suitable shape, being shown as rectangular in a particular embodiment in Fig. 5. Notch 12 may be forward or rearward of the angular cut previously described as the circumstances warrant. Fig. 5

shows one embodiment with notch 13 rearward of cut 12. This notch 13 engages a shoulder 5 and thereby prevents longitudinal movement of the contact strip. A further purpose of notch 13 is that when it is cut at a predetermined position, it will insure the uniform protruding length of all contacts in the bank. Forward ends 14 and rearward ends 15 of contact strips 1 protrude beyond the bank in well known manner and said ends are not of unfamiliar design in the art.

To form now a contact bank or pileup, it is only necessary to pile up a predetermined number of insulator elements 2 equipped with contact strips 1 as hereinbefore described, one upon another until the desired number of rows is reached. The uppermost insulator element 16 is then added but without contact strips in its upper depressions. At this stage, all lower elongations 7 neatly dovetail into upper depressions 6, with appendages 9 lightly resting centrally upon next lower contact strips 1.

This assemblage is then topped with a conventional clamping plate 3 which contains holes or perforations aligned with those in the insulator elements.

The bottom of this pileup is then fitted into a bottom insulator element 17, shown in Fig. 7, which for all practical purposes is identical to the insulator elements 2 described hereinbefore with the exception that lower appendages 9 are not present, and the lower raised edges may be longer. In the embodiment shown in Fig. 7, bottom insulator 17 is shown to have somewhat longer lower edges 18.

Beneath the bottom insulator 17 is placed another clamping member 3 described hereinbefore.

Application of compression means 4, will now complete the bank. All elongations 7 dovetail tightly into depressions 6, snugly holding contact strips 1 while appendages 9 being slightly greater in depth than the lower elongations 7 press down centrally on all contact strips causing them to flex or bow slightly.

In this position the contact bank is complete. Notches 13 co-operating with shoulders 5 along with the bows in the contact strips due to the action of the compression means 4 and appendages 9 upon strips 1 hold strips 1 fixed and without longitudinal motion while the seating arrangement provided for the contact strips 1 by depression 6 will hold said strips free from lateral motion.

An additional factor to be noted is the slight compressibility of the relatively small area raised edges of insulator elements 2, which allow for maintaining close tolerances both for overall dimensions of the contact bank as well as for distances between the various levels of contacts.

Having described our invention in detail what we claim and desire to be protected by issuance of Letters Patent of the United States is:

1. In a switch bank, a plurality of molded insulator elements one upon another, raised edges on said insulator elements, upper raised edges right and left having alternately shoulders and depressions respectively aligned in pairs, lower raised edges right and left having alternately elongations and recessions respectively aligned in pairs, said elongations immediately below said depressions, contact strips laying in said aligned depressions and protruding therebeyond, said elongations dovetailing into said depressions of a next lower insulator element and said recessions

on said lower raised edges receiving said shoulders of said next lower supports, and means to compress said elements, said shoulders, depressions, recessions, elongations and raised edges being so constructed as to hold said contact strips firmly in place and said insulators together under the compression of said means.

2. In a switch bank as claimed in claim 1, semi-cylindrical appendages longitudinally between said lower edge elongations, the depth of said appendages being slightly greater than one of said elongations and substantially equal to the other, said appendages co-operating with said means to bow said contact strips immediately thereunder upon application of said means.

3. In a switch bank as claimed in claim 1, said insulator elements having a plurality of aligned perforations between said contact strips, said perforations to accept said compression means.

4. In a switch bank substantially as claimed in claim 1, said insulator strips comprising a molded synthetic resin.

5. In a switch bank substantially as claimed in claim 1, said insulator strips comprising molded polymerized ethylene.

6. In a switch bank, a plurality of contact strips, a plurality of semi-circular insulator elements, raised edges on said insulator elements, each of said insulator elements comprising a plurality of radially equal integral components; every other radial component having its lower edges elongated fore and aft and a semi-cylindrical appendage longitudinally therebetween of slightly greater depth than one of said elongated lower edges and substantially equal to the other, while the upper edges right and left immediately thereabove are depressed, the depth of said depression being the thickness of a contact strip plus the depth of a lower edge elongation; and therebetween every other radial component having shouldered upper edges right and left and recessed lower edges right and left; a contact strip laying in each pair of upper depressions right and left and projecting therebeyond, insulator elements so equipped with contact strips stacked one above another in a pileup, elongated edges fitting into depressions; and compression means to hold said strips and insulator elements together, said depressions and said compression means co-operating with said semi-cylindrical appendages and raised edges to cause a bow in said contact strips and fixedly hold them in place.

7. In a switch bank as claimed in claim 6, said bowed contact strips comprising equal lengths of metal, one lateral edge thereof having two indentations, one indentation being obtusely angular in shape, the vertex of which is the longitudinal and lateral center point of said contact strip, the other indentation being a rectangular notch rearward of said first indentation, said one indentation functioning to circumvent said compression means, said other notchlike indentation engaging an upper aft raised edge portion co-operating with said compression means to fixedly hold said contact strips in place.

8. In a switch bank, a plurality of bowed contact strips, a plurality of molded semi-circular insulator elements, raised edges on said insulator elements, the upper right and left raised edges of said insulator elements having alternate depressions and shoulders therein, said bowed contact strips laying in corresponding pairs of depressions right and left, and the lower right and left raised edges of said insulator elements alternately

elongated and recessed, elongations of lower edges immediately beneath depressions in upper edges, and longitudinally between said lower edge elongations semi-cylindrical appendages slightly greater in depth than one of said lower edge elongations and substantially equal to the other; a predetermined number of such insulator elements with contact strips stacked one upon another in a pileup, lower edge elongations of the next higher fitting into upper edge depressions of the next lower, the uppermost insulator element being deprived of said contact strips, semi-circular clamping plates above and below said pileup, and compression means to vertically compress said pileup, said means co-operating with said semi-cylindrical appendages resting centrally on the next lower contact strip, and further co-operating with the dovetailing of said elongations into corresponding depressions so as to cause said contact strips to bow and said elongations and depressions to mesh holding all constituents fixedly in place.

9. In a switch bank, a plurality of insulator supports arranged in layers, a plurality of contact strips in spaced apart relationship between said layers, compression means in said bank to vertically compress said layers, and means integral with said insulator supports for causing said strips to deflect upon application of said compression means to cooperate with said supports to rigidly fix said strips in position in said bank.

10. In a switch bank, a plurality of semi-circular insulator supports arranged in layers, a plurality of contact strips in a radial spaced apart relationship between said layers, compression means in said bank to vertically compress said layers, and means integral with said insulator supports for causing said strips to deflect upon application of said compression means to cooperate with said supports to rigidly fix said strips in position in said bank.

11. In a switch bank, a plurality of insulator supports arranged one upon the other having apertures therein, a plurality of flat contact strips arranged in a spaced apart relationship between each of said insulator supports and projecting transversely through said supports through said apertures, compression means in said bank for vertically compressing said supports one upon the other to hold said strips in said apertures, and means integral with said support for causing said strips to bow upon application of said compression means.

12. In a switch bank, a plurality of formed insulator supports, having projections and recesses thereon, arranged in a stratified manner, the projections of one of said supports partly engaging corresponding recesses in a support in the next stratum, contact strips passing transversely through said recesses in said supports and extending therebeyond, central projections in said supports transversely aligned with the recesses in the support in said next stratum, and compression means in said bank for vertically compressing said stratified arrangement to cause said central projections to deflect said strip and to cooperate with said partial engagement to fix position of said strip in said bank.

13. In a switch bank, a plurality of contact strips arranged in rows in a spaced apart relationship, insulator supports separating said rows, a plurality of downward projections on opposing sides of said supports transversely aligned, said supports also having a plurality of recesses on

opposing sides of the upper surface thereof, said recesses in transverse alignment with each other and in vertical alignment with said downward projections, said recesses of a depth greater than said projections by the depth of said contact strips, said downward projections of one of said supports projecting into said vertically aligned recesses of the next lower support, said contact strips resting transversely in said recesses and extending beyond said supports, central downward projections integral with said supports in transverse alignment with said downward projections and located therebetween, said central downward projections having a depth greater than one of said downward projections and substantially equal to the other, compression means to compress said supports vertically to cause said projections and recesses to firmly grip said strips to prevent lateral movement thereof, and to cause said central downward projections to deflect said strips to cooperate with said projection and recesses to prevent longitudinal movement of said strips thereof.

14. In a switch bank, a plurality of insulator supports arranged in layers, a plurality of contact strips arranged in a spaced apart relationship between said layers, means integral with said supports for preventing lateral movement of said strips in said support, means integral with said strips for interlocking with said integral support means to prevent longitudinal movement of said strips in said support, compression means to vertically compress said layers, and other means integral with said supports for causing said strips to deflect upon application of said compression means to further prevent longitudinal movement thereof.

15. In a switch bank, a plurality of insulator supports arranged in layers, a plurality of contact strips arranged in a spaced apart relationship between said layers, means integral with said supports for preventing lateral movement of said strips between said layers, notches in said strips interlocking with said means for preventing longitudinal movement of said strips between said layers, compression means to compress said layers vertically upon said strips, and other means integral with said supports for bowing said strips upon application of said compression means to further prevent longitudinal movement thereof.

16. In a switch bank, a plurality of insulator supports arranged in layers, raised edges on the upper surfaces of said supports, depending edges on the lower surfaces of said supports, said edges

having alternately spaced shoulders, the shoulder of the upper edge offset from the shoulder on the lower edge thereof, contact strips between said support layers, said contact strips resting between 5 said raised edge shoulders and overhanging said supports, said depending edge shoulder of a higher support also resting between said raised edge shoulders of the next lower support directly over said contact strips, compression means to vertically compress said layers to retain said strips fixed between said shoulders, a central depending projection from said lower surface, said central depending projection bowing said contact strip upon application of said compression means to further retain said strips between said shoulders.

17. In a switch bank, a plurality of insulator supports arranged in layers, raised edges on the upper surface of said supports, shoulders on said 20 raised edges, depending edges on the lower surface of said supports, shoulders on said depending edges, said shoulders on said upper edges transversely aligned in pairs, said shoulders on said lower edges also aligned in pairs, said lower edges vertically offset from said upper edge shoulders so that said layers of supports 25 intermesh, a plurality of contact strips resting between said upper edge shoulders and enclosed by said intermeshing of said layers, rectangular notches in said contact strips, said notches engaging said raised edge shoulders to prevent longitudinal movement of said strip through said supports, a central depending projection on the lower surface of said supports of greater length 30 than one of said depending edge shoulders and substantially equal to the other, said central dependent projection laterally offset from said depending edge shoulders, and compression means for compressing said layers vertically, said depending central projection flexing said contact strip to further prevent longitudinal movement thereof upon application of said means.
